H. WALKENHORST

HATPIN FASTENER

Filed Aug. 14, 1922

Inventor

Herman Walkenhorst.

By his Attorney

Marvin Palmer

UNITED STATES PATENT OFFICE.

HERMANN WALKENHORST, OF MILTON, KENTUCKY.

HATPIN FASTENER.

Application filed August 14, 1922. Serial No. 581,599.

To all whom it may concern:

Be it known that I, HERMANN WALKENHORST, a citizen of Germany, residing at Milton, in the county of Trimble and State 5 of Kentucky, have invented certain new and useful Improvements in Hatpin Fasteners, of which the following is a specification.

This invention relates to devices for securing women's hats in adjusted position on 10 their heads and has as one of its objects to provide a pin having a helical portion, near its ornamental head, capable of effectively engaging the hair in a manner not liable to accidental displacement.

15 Another purpose is to produce a pin point protector, made of an inherently flexible material adapted to frictionally receive and grip the entering point of the pin.

A further aim is in the provision of an 20 unusually light pin protector, capable of receiving ornamentation, and which is relatively inexpensive to manufacture.

These objects are attained by the novel 25 construction and arrangement of parts hereinafter described and shown in the accompanying drawing, forming a material part of this disclosure, and in which:—

Figure 1 is a perspective view showing 30 the application of a pin made in accordance with the invention.

Figure 2 is a side view of the pin and 35 protector, the latter being shown in section.

Figure 3 is a fragmentary perspective 40 view illustrating the coils in the pin shaft.

Two principal requirements are desirable 45 in pins of this character, one being that the pin be securely but removably engaged in the hair, without unnecessarily puncturing the hat, and the other is a guard or fender for preventing the exposed point of the pin from 50 doing damage to other people in close proximity.

With these requirements in mind, the pin 55 is shown to be composed of a head of any

fanciful form preferred, capable of being 45 firmly grasped in manipulating and to present a pleasing appearance.

The pin shaft 6 is twisted to present an 50 outstanding helical coil 7 at a short distance from the head but far enough to enable the pin to be turned in the manner of a screw whereby the coil is passed through the side of the hat and engaged with the hair of the wearer to effectively prevent it from inadvertent withdrawal.

55 The continuing, main portion 8 of the pin shaft is straight and terminates in a long taper point 9 passed through the opposite side of the hat as shown.

The protector or keeper 10 is made in any 60 preferred form from cork, this material being very light and inexpensive, and as is well known, possesses a high degree of elasticity, and frictionally adheres to the entered point with great tenacity.

An opening 11 is formed in the inner end 65 of the protector and at the end of the opening may be set a small plug 12 of lead or other soft metal, the same preventing the pin from piercing the full length of the cork, 70 acting as a stop for the point without injuring it.

75 Preferably the protector is enamelled with colors and shaped to present a large head, the better to operate the same and also to provide a relatively large area for contact with persons or objects in close proximity.

Having thus described my invention, what I claim as new and desire to secure by Letters Patent, is:—

80 A pin protector comprising a cork shaped for manual operation, said cork containing an axial opening at the smaller end, and a plug of soft metal embedded in said cork at the bottom of the mentioned opening.

85 In witness whereof I have affixed my signature.

HERMANN WALKENHORST.
